(57) **CLAIM**

The ornamental design of an automotive spindle, as shown and described.

DESCRIPTION

FIG. 1 is a top plan view of an automotive spindle according to my new design;

FIG. 2 is a right side elevation view of the automotive spindle shown in FIG. 1;

FIG. 3 is a bottom plan view of the automotive spindle shown in FIG. 1;

FIG. 4 is a left side elevation view of the automotive spindle shown in FIG. 1;

FIG. 5 is a left end elevation view of the automotive spindle shown in FIG. 1;

FIG. 6 is a right end elevation view of the automotive spindle shown in FIG. 1;

FIG. 7 is a right front perspective view of the automotive spindle; and,

FIG. 8 is a left front perspective view of the automotive spindle.

The broken lines depict portions of the automotive spindle that form no part of the claim.
